[57] CLAIM

The ornamental design for a breast implant enhancer, as shown and described.

DESCRIPTION

FIG. 1 is a perspective view of a breast implant enhancer, showing our new design;

FIG. 2 is a top plan view thereof;

FIG. 3 is a side elevational view thereof, the opposite side being identical thereto; and

FIG. 4 is a cross-sectional view taken along line 4—4 of FIG. 2.

The bottom of the article is substantially plain and unornamented.

FIG. 1

FIG. 2

FIG. 3

FIG. 4
